Primary Examiner — Robert Delehanty

(74) Attorney, Agent, or Firm — Banner & Witcoff, Ltd.

(57) **CLAIM**

The ornamental design for a faucet, as shown and described.

DESCRIPTION

FIG. 1 is a front perspective view of a faucet showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line showing of the spout opening in FIGS. 2 and 7 and the three circular base regions in FIG. 7 represents unclaimed areas and forms no part of the claim design.

1 Claim, 4 Drawing Sheets(56)
